(57) CLAIM

The ornamental design for a modular storage bag, as shown and described.

DESCRIPTION

FIG. 1 is a perspective view of the modular storage bag.

FIG. 2 is a right side view of the modular storage bag.

FIG. 3 is a left side view of the modular storage bag.

FIG. 4 is a front view of the modular storage bag.

FIG. 5 is a rear view of the modular storage bag.

FIG. 6 is a top view of the modular storage bag; and,

FIG. 7 is a bottom view of the modular storage bag.

The broken lines illustrate portions of the modular storage bag and form no part of the claimed design.
